UNITED STATES PATENT OFFICE.

CLARENCE L. CAMP, OF SPOKANE, WASHINGTON.

DESIGN FOR SUSPENDERS.

49,418.

Specification for Design. Patented July 25, 1916.

Application filed May 10, 1916. Serial No. 96,736. Term of patent 14 years.

To all whom it may concern:

Be it known that I, CLARENCE L. CAMP, a citizen of the United States, residing at Spokane, in the county of Spokane, State of Washington, have invented a new, original, and ornamental Design for Suspenders, of which the following is a specification, reference being had to the accompanying drawing, forming a part thereof.

Figure 1 is a view of my suspender taken

from the rear. Fig. 2 is a view thereof taken from the front.

I claim:

The ornamental design for suspenders, substantially as shown.

CLARENCE L. CAMP.

Witnesses:

H. E. SMITH,
H. P. BONFFLEUR.
